UNITED STATES PATENT OFFICE

KENNETH R. D. WOLFE, OF MARSHALLTOWN, IOWA, ASSIGNOR TO THE FISHER GOVERNOR COMPANY, OF MARSHALLTOWN, IOWA

GAS REGULATOR

Application filed October 8, 1928. Serial No. 311,189.

My invention consists in new and useful improvements in gas pressure regulators, and has for its object to provide a device of this character, which is simple in construction and 5 operation, and one which is purely automatic in its function.

Another object of my invention is to provide adjustable automatic means for controlling the pressure of gas or other fluid passing 10 through a pipe line.

A still further object of my invention is to increase the sensitiveness of the regulator by eliminating a number of the usual bearings and frictional connections.

15 With the above and other objects in view which will appear as the description proceeds, my invention consists in the novel features hereinafter described in detail, illustrated in the accompanying drawings, and more particularly pointed out in the appended claims.

Referring to the drawings, in which numerals of like character designate similar parts throughout the several views,

Fig. 1 is a view in vertical cross section, of 20 one form of my invention.

Fig. 2 is a similar view of another embodiment employing the same general principle, but disclosing the use of a plurality of crossed spring strips in place of the coil spring for 25 opposing the gas pressure on the diaphragm,

Fig. 3 is a view of a further modification of my invention, illustrating an arrangement wherein the inlet valve operates in the reverse direction.

30 Fig. 4 is an enlarged detail of the inlet valve shown in Figs. 1 and 2.

Fig. 5 is a similar view of the inlet valve shown in Fig. 3.

In Fig. 1 of the drawings, 1 represents the 35 main body or casing of the regulator, which consists of upper and lower members 2 and 3 respectively. The lower member or chamber 3, is substantially bowl-shaped, and provided upon its under surface with supports 4, for securing the same in place. In one 40 wall of the chamber 3, I provide an outlet aperture 5, threaded to receive a suitable connection, and in the opposite wall, I provide an inlet opening 6, adapted to receive an inlet 45 valve, as hereinafter set forth.

The upper member 2 of the casing 1, is somewhat similar in shape to an inverted bowl, having an upwardly extending tube or neck 7, located centrally thereof. The members 2 and 3 are secured together in opposed relation with a diaphragm 8, interposed therebetween, by means of a plurality of threaded bolts 9, adapted to be inserted at predetermined points around the peripheries of said members.

10 represents a coil spring rotatably secured to the upper surface of the diaphragm 8, by means of a recessed supporting disk 11, pivotally mounted on said diaphragm by a threaded screw 12, which extends downwardly 45 through said diaphragm into a disk 13 on the under side thereof. The spring 10 extends upwardly through the neck 7 of the casing 1, and carries at its upper end a second recessed supporting disk 14, which is centrally apertured to receive a downwardly projecting centering lug 15 on the under side of the top of the adjusting member 16. This adjusting member 16 is cylindrical in shape, and its outer walls are threaded to engage corresponding threads at the upper extremity of the neck 7, whereby when said member 16 is screwed downwardly, spring 10 will become compressed, and when screwed outwardly, said spring will be permitted to expand.

The upper extremity of the neck 7 is reduced to receive a cap or cover 17, which is secured in place by means of a screw 18, also adapted to serve as a set screw for locking the adjusting member 16 at the desired point.

19 represents an inlet valve adapted to be secured in the inlet aperture 6 of the casing 1, and consists of a body portion 20, threaded at its outer end to engage a locking nut 21, and provided toward its inner end with a projecting ring 22 for engaging a circular recess in the wall of the chamber 3, just inside the inlet aperture 6, whereby when said nut 21 is tightened, said body member 20 is drawn outwardly and secured tightly in 55 place within the aperture 6. Inside the valve body 20, and adapted to move longitudinally therein, is a valve head 23, its outer conical end adapted to seat at 24. The inner end of the valve head 23 is secured to 60

one end of a strip 25 of suitable flexible metal, the other end of which is secured to an upwardly projecting post 26 within the chamber 3 of the casing 1.

- 8. The disk 13 on the under surface of the diaphragm 8, is provided with a downwardly extending lug 27, to which the central portion of the strip 25 is loosely secured, as at 28.
- 10. The embodiment shown in Fig. 2 is practically identical to the device just described, with the exception of the shape of the upper member 2 of the casing 1, and the spring for opposing the pressure on the under surface of the diaphragm. In this arrangement, instead of the coil spring 10, I provide two or more crossed, bowed spring strips 29 and 30, the central portions of which are secured together by a rivet or 20 other suitable connection 31, while their free ends engage and press against the upper surface of the diaphragm 8. 32 represents an adjusting screw which is threaded to engage the inner threads of the neck of the upper member 2 of the casing 1, its lower extremity contacting with the central portion of the uppermost spring strip 29, and its upper extremity being slotted to receive a screw driver or other suitable instrument.
- 28. This screw 32 may be locked in the desired position by a lock nut 33, and is enclosed by a suitable cap 34, which is adapted to be screwed on to the external threads of the neck of the casing.
- 35. Having thus described in detail the construction and arrangement of parts of my improved gas pressure regulator, its operation is as follows.

Assuming that the device is connected in 40 a gas or other pipe line with the fluid passing through the same from the inlet 6 to the outlet 5, the diaphragm spring 10, or 29 and 30, as the case may be, is adjusted to the desired tension to maintain a constant, even 45 pressure on the discharge side of the valve 19. If the pressure increases in the chamber 3, the diaphragm 8 is forced upwardly against the pressure of the opposing spring, and causes the disk 13 to rise, and with it the lug 27, which in turn tends to straighten out the spring strip 25, by raising its central portion, thus causing the valve head 23 to move longitudinally toward the seat 24, to reduce the inlet aperture. On the other 55 hand, if the pressure in the chamber 3 decreases, the opposing diaphragm spring will expand and cause said diaphragm to be forced downwardly thus drawing the valve head inwardly away from its seat 24, to permit of the passage of more fluid through said valve.

In the modification illustrated in Fig. 3, the resilient strip 25 is flexed in the opposite direction from those heretofore described, 65 which is accomplished by reducing the

length of the downwardly projecting lug 27 on the disk 13. The valve body 23, secured to the free end of the strip 25, is not of the needle type which seats from the interior, as in Figs. 1 and 2, but is of the external seating type, as clearly shown in the drawings. 70

Thus, when, with the reduction of pressure within the chamber 3, the diaphragm moves downwardly, the lug 27 tends to straighten out the strip 25 and forces the valve head 23 outwardly to open the inlet aperture. With the reverse movement of the diaphragm, on the increase of pressure in chamber 3, the valve head is drawn inwardly and seated, to restrict the inlet aperture. 80

From the foregoing, it is believed that the construction, operation and advantages of my invention may be readily understood by those skilled in the art, and I am aware that changes may be made in the details disclosed, without departing from the spirit of the invention, as expressed in the following claims. 90

What I claim and desire to secure by Letters Patent is:

1. A fluid regulator, comprising a casing, a valve and valve seat in said casing, a diaphragm in said casing, a strip of flexible material rigidly secured at one end, its other end being directly fastened to said valve, and a connection between said diaphragm and the intermediate portion of said strip, whereby the movement of the diaphragm is transmitted directly to said valve. 100

2. A fluid pressure regulator comprising a casing, a diaphragm separating said casing into two chambers, one of which is in communication with the fluid being regulated, a spring mounted in the other chamber in contact with said diaphragm for opposing the fluid pressure, a longitudinally movable valve in said fluid chamber, a strip of flexible metal rigidly secured at one end within said last named chamber, its other end being directly fastened to said valve, and a connection between its intermediate portion and to said diaphragm, whereby the movement of the latter is transmitted directly to said valve. 110 115

3. A fluid regulator as claimed in claim 1 wherein said valve is of the external seating type.

4. A fluid regulator comprising a casing having inlet and outlet openings, a cylindrical sleeve in said inlet opening, a seat within said sleeve exterior of said casing, a valve extending through said sleeve and adapted to reciprocate therein, said valve having an enlarged head also exterior of said casing and adapted to engage said seat on the latter's inlet face, a diaphragm in said casing, a strip of flexible material rigidly secured at one end, its other end being directly fastened to said valve, and a connection between said dia- 120 125

- phragm and the intermediate portion of said strip whereby the movement of the diaphragm is transmitted directly to the valve to open or close said inlet.
5. A fluid regulator, comprising a casing, a valve and valve seat in said casing, a diaphragm in said casing, a strip of flexible material secured at one end, its other end being directly fastened to said valve, and a connection between said diaphragm and the intermediate portion of said strip, whereby the movement of the diaphragm is transmitted directly to said valve.
6. A fluid pressure regulator comprising a casing, a diaphragm separating said casing into two chambers, one of which is in communication with the fluid being regulated, a spring mounted in the other chamber in contact with said diaphragm for opposing the fluid pressure, a longitudinally movable valve in said fluid chamber, a strip of flexible metal secured at one end within said last named chamber, its other end being directly fastened to said valve, and a connection between its intermediate portion and said diaphragm, whereby the movement of the latter is transmitted directly to said valve.
7. A fluid regulator comprising a casing having inlet and outlet openings, a cylindrical sleeve in said inlet opening, a seat within said sleeve exterior of said casing, a valve extending through said sleeve and adapted to reciprocate therein, said valve having an enlarged head also exterior of said casing and adapted to engage said seat on the latter's inlet face, a diaphragm in said casing, a strip of flexible material secured at one end, its other end being directly fastened to said valve, and a connection between said diaphragm and the intermediate portion of said strip whereby the movement of the diaphragm is transmitted directly to the valve to open or close said inlet.
8. In a pressure regulator, the combination of: a body forming a pressure chamber and having an inlet and an outlet; a diaphragm forming a wall of said chamber and having a central stud extending into said chamber; a valve for said inlet having an operating movement in a plane at right angles to the axis of said diaphragm; means for applying a predetermined pressure to the outer surface of said diaphragm; and a single bowed leaf-spring toggle member directly connected to said stud and valve for transmitting the movements of said diaphragm to said valve, said toggle member reducing the movements and increasing the power transmitted thereby.
9. In a pressure regulator, the combination of: walls forming a pressure chamber and an inlet and outlet therefor; a pressure-responsive member forming a wall for said pressure chamber and being acted upon by the pressure in said pressure chamber; regu- lating means for exerting a force on said pressure-responsive member in opposition to the force applied by the gas pressure in said pressure chamber; a valve for closing said inlet, said valve being movable in a plane at an angle to the movement of said pressure-responsive member; a toggle formed of a one-piece spring for operating said valve, one end of said toggle engaging said valve; and connecting-means for connecting said toggle and said pressure-responsive means whereby said toggle is moved by said pressure-responsive means, said toggle being straightened as said valve moves toward closed position so that the force applied to said valve gradually increases.
10. In a pressure regulator, the combination of: walls forming a pressure chamber, and an inlet and an outlet therefor; a pressure-responsive member forming a wall for said pressure chamber; regulating means for exerting a force on said pressure-responsive member; a valve for said inlet, said valve being movable to open and close said inlet in a plane at an angle to the movement of said pressure-responsive member; a one-piece toggle-spring, one end directly engaging said valve and the other end engaging said walls forming said pressure chamber, said toggle-spring being bowed by compression so that said toggle yieldingly tends to hold said valve in closed position; and connecting means operatively connecting said toggle-spring and said pressure-responsive member.
11. In a pressure regulator, the combination of: walls forming a pressure chamber, and an inlet and an outlet therefor; a pressure-responsive member forming a wall for said pressure chamber; regulating means for exerting a force on said pressure-responsive member; a valve for said inlet, said valve being movable to open and close said inlet in a plane at an angle to the movement of said pressure-responsive member; a one-piece toggle-spring, one end directly engaging said valve and the other end pivotally engaging said walls forming said pressure chamber, said toggle-spring being bowed by compression so that said toggle-spring yieldingly tends to hold said valve in closed position; and connecting means operatively connecting said toggle-spring and said pressure-responsive member.
12. In a pressure regulator, the combination of: body forming a pressure chamber having an outlet; a diaphragm forming a wall of said chamber and having a central stud extending into said chamber; means for applying a predetermined pressure to the outer surface of said diaphragm; an inlet nozzle associated with said chamber and positioned in a plane at right angles to the axis of said stud and forming a valve seat; a valve slidably associated with said nozzle; and a single toggle member associated with said

stud and having its ends connected to said valve and said body for transmitting the movements of said diaphragm and said stud to said valve, said toggle member reducing the movements and increasing the force transmitted thereby.

13. A fluid regulator, comprising a casing, a valve of the external seating type and valve seat located exterior of said casing, a diaphragm in said casing, a strip of flexible material secured at one end, its other end being directly fastened to said valve, and a connection between said diaphragm and the intermediate portion of said strip, whereby the movement of the diaphragm is transmitted directly to said valve.

14. A fluid regulator comprising a casing having inlet and outlet openings, a cylindrical sleeve exterior of said casing, a valve extending through said sleeve and adapted to reciprocate therein, said valve having an enlarged head also exterior of said casing and adapted to engage said seat on the latter's inlet face, a diaphragm in said casing, a strip of flexible material secured at one end, its other end being directly fastened to said valve, and a connection between said diaphragm and the intermediate portion of said strip whereby the movement of the diaphragm is transmitted directly to the valve to open or close said inlet.

In testimony whereof I affix my signature.

KENNETH R. D. WOLFE.
